UNITED STATES PATENT OFFICE

HENRY F. ASCHECK, OF SAN FRANCISCO, CALIFORNIA.

TUBE OR TUNNEL PROTECTOR FOR CABLE ROADS.

SPECIFICATION forming part of Letters Patent No. 400,034, dated March 26, 1889.

Application filed August 16, 1888, Serial No. 282,934. (No model.)

To all whom it may concern:

Be it known that I, HENRY F. ASCHECK, of the city and county of San Francisco, State of California, have invented an Improvement in 5 Tube or Tunnel Protectors for Cable Roads; and I hereby declare the following to be a full, clear, and exact description of the same.

My invention relates to the class of cable railroads. My invention consists in a plate 10 pivoted or hinged within the tube or tunnel to one side thereof, said plate traversing or crossing the vertical plane of the grip-slot and resting against the other side of the tube or tunnel, whereby when at rest it covers the top 15 or neck of the tube, but is adapted to be moved by the passing grip without interfering with its travel.

My invention further consists in the construction and arrangement of a continuous 20 series of said plates, their connections and limiting devices, and other details, all of which I shall hereinafter fully describe.

The object of my invention is to protect the 25 tube or tunnel from snow, dust, dirt, sand, and other débris which usually finds its way through the open grip-slot into said tube or tunnel and interferes with the proper working of the cable, the carrying-sheaves, and other machinery located in the tube or tunnel.

Referring to the accompanying drawings for 30 a more complete explanation of my invention, Figure 1 is a cross-section of a cable-railway tube or tunnel, showing the application of my invention. Fig. 2 is a perspective view of a series of my protecting-plates, showing their relative arrangement. Fig. 3 is a top view of same, showing the effect of the passing grip-shank. Fig. 4 is a view showing the application 40 of the plates to a curve.

A is the tube or tunnel, formed in any suitable manner, a yoke, *a*, being here shown as part of the frame-work or skeleton.

B is the grip-slot, formed by the slot-irons 45 *b* in the top of the tube or tunnel.

C is a carrying-sheave for the cable D.

E is the grip-shank. (Shown in dotted lines in Fig. 1 and in horizontal cross-section in Fig. 3.)

50 F is my protecting-plate. By reference to Fig. 1 it will be seen that it is located within

the tube or tunnel at its upper portion or neck and crosses the vertical plane of the grip-slot and the path of the grip-shank. It is hinged or pivoted in the tube or tunnel in 55 a suitable manner, so that it may be moved by the passing grip-shank to one side of the vertical plane of the grip-slot, and after being relieved by the grip-shank it is adapted to return to its normal place.

To hinge or pivot the plate, I have here shown, as one form of connection a rod, *G*, which is to be fixed in suitable manner within the tube or tunnel, as by the carrying-brackets *H* bolted to the flanged yokes *a*. The 65 plate *F* is fitted to this rod by means of eyes or staples *f*, secured to the plate and loosely embracing the rod, said eyes or staples representing one form of hinge, and at the same time serving a further purpose, which will 70 presently appear. The line on which the plate is hinged is below the center, thereby enabling the plate to return to its seat by gravity, and the plate is wide enough to find a seat against the opposite side of the tube or 75 tunnel—here shown as against the side of the opposing slot iron *b*. This is its normal position. It will now be seen that when in this position it serves as a protector for the tube or tunnel by preventing the snow, dust, dirt, sand, 80 &c., which enters the slot from falling directly upon the cable and carrying-sheaves below; but when the grip-shank comes in contact with the edge of the plate it moves said plate to one side of the vertical plane of the slot, as 85 shown by the dotted lines in Fig. 1, and thus opens the slot for the free passage of the grip. In this position—namely, that of the dotted lines, Fig. 1—whatever débris may have lodged and accumulated on the plate is directed 90 downwardly toward the side of the tube or tunnel, and may fall to the bottom thereof, passing down one side, and not coming in contact with the machinery at all; or, if desired, a receptacle—such as is represented by *J*—may 95 be secured to the side of the tube or tunnel and receive the débris. As soon as the grip relieves the plate *F*, it returns by gravity to its seat. If found desirable, a spring, *K*, may be employed to assist the plate in returning 100 to its seat. I have in Fig. 1 shown the spring as connected with the plate below its pivotal

center and arranged to draw the lower portion of the plate toward the side of the tube or tunnel, thereby throwing the upper end of the plate over to its seat.

5 In Fig. 2 I show the manner of arranging the plates F in continuous series throughout the length of the road. An overlapping flange, f', is formed or placed on the end of each plate, this flange extending over to and 10 lying against the surface of the end of the adjacent plate. Therefore when the grip-shank presses against one plate the side movement of said plate is communicated to the adjacent plate and it moves over also; but in order to 15 avoid having to move the whole line or series of plates by pressure applied to one I make the hinge staples or eyes f loose enough on the fixed rod G to permit enough play to the plates to allow all to remain in normal position, except those in the immediate vicinity of the grip-shank. This result and the position of the plates under the action of the grip-shank I have shown in Fig. 3. Thus only that portion of the grip slot and tube or tunnel which 25 is in the immediate vicinity of a car will be temporarily uncovered, the remaining portion being protected by the plates resting in normal position.

As a car has sometimes to be moved back, 30 I provide for the proper connection of the plates by means of other flanges or arms, L, secured to the under side of one end of the plate and overlapping the adjacent plate. These will communicate motion from one 35 plate to the other when the car is backing, and in this case the loose eyes or staples serve the same function as before. The flanges f' and L, being on opposite sides of the plates, prevent them from slipping by each other and 40 hold them in place on the rod.

In a curve, where it might be impracticable to extend the rod G all the way around, I could terminate it on each side, as shown in Fig. 4, allowing its ends to project sufficiently 45 to hinge a central curved plate thereto; or short rods might be used in the curve, if found desirable.

I am aware that covers for slots of cable railways are not new, and that hinged or swinging plates have been placed over and also immediately under the slot; but I am not aware of a plate located within the neck of the tube or tunnel itself, and so arranged as to direct the débris down to one side, thus avoiding 55 dropping it upon the cable machinery.

Having thus described my invention, what I claim as new, and desire to secure by Letters Patent, is—

1. In a cable railway, a plate hinged or pivoted within the tube or tunnel, to one side thereof, said plate crossing the vertical plane

of the grip-slot and resting against the opposite side of the tube or tunnel, substantially as herein described.

2. In a cable railway, a plate hinged or pivoted within the tube or tunnel, to one side thereof, said plate extending at an upward inclination to and resting against the opposite side, whereby when at rest it crosses the vertical plane of the grip-slot and can be moved 65 over to one side of said plane by the passing grip, substantially as herein described.

3. In a cable railway, a plate within the tube or tunnel crossing the vertical plane of the grip-slot and resting against one side of 75 said tube or tunnel, said plate having a hinge or pivot connection with the other side of the tube or tunnel on a line below the center of the plate, whereby it finds its seat by gravity, substantially as herein described.

4. In a cable railway, the tube or tunnel having a fixed rod secured to one side thereof, in combination with a plate hinged or pivoted on said rod and crossing the vertical plane of the grip-slot to the other side, where it finds 85 a rest, substantially as herein described.

5. In a cable railway, the tube or tunnel having a fixed rod secured to one side thereof, in combination with a plate hinged or pivoted on said rod on a line below its center, whereby 90 it finds its seat by gravity, said plate extending at an upward inclination across the vertical plane of the grip-slot and resting on the other side, substantially as herein described.

6. In a cable railway, the series of hinged 95 plates within the tube or tunnel and crossing the vertical plane of the grip-slot, said plates having flanges overlapping the edge of the plate adjacent, substantially as herein described.

7. In a cable railway, the series of hinged plates within the tube or tunnel and crossing the vertical plane of the grip-slot, said plates having flanges overlapping the edge of the plate adjacent and having a play in their 105 hinge-connection, whereby only those plates in the vicinity of the passing grip-shank will be moved, substantially as herein described.

8. In a cable railway, the tube or tunnel having the fixed rod, in combination with the 110 series of plates within the tube or tunnel and crossing the vertical plane of the grip-slot, said plates having overlapping flanges, and the staples or eyes loosely embracing the rod, whereby the plates are hinged thereto, substantially as herein described.

In witness whereof I have hereunto set my hand.

HENRY F. ASCHECK.
